UNITED STATES PATENT OFFICE.

MARCEL WALLACE, OF NEW YORK, N. Y., ASSIGNOR TO ELECTRO-LABORATORIES, INC., OF NEW YORK, N. Y., A CORPORATION OF NEW YORK.

RADIO RECEIVING APPARATUS.

Application filed April 27, 1925. Serial No. 26,207.

My invention relates broadly to radio receiving apparatus and more particularly to a complete radio receiver arranged to derive its power from the usual house lighting circuit without the employment of primary or

5 secondary batteries. general resistances due to drop in voltage along the resistances, the resistances being connected in a series circuit and supplied from a common source of direct current energy.

55 A still further object of my invention is to provide a radio receiving system operated from the house lighting circuit in which the drop along a plurality of resistances disposed in series may be utilized for energizing the cathode and anode circuits for the several tubes and also for establishing the proper grid potential for the several tubes 60 without the employment of separate sources 65 of potential for biasing the grid electrodes in the several tubes.

My invention will be more clearly understood from the following specification by 70 reference to the accompanying drawings in which Fig. 1 is a wiring diagram illustrating the principle of my invention; and Figs. 2 and 3 are modified arrangements of the cathode circuits employed in my receiver 75 design.

75 In constructing radio receiving apparatus for operating from the house lighting circuit, I have found that in order to meet local conditions in different cities throughout the country it is desirable that the receiving apparatus be designed to operate both from an alternating current power supply and a direct current power supply by 80 reason of the different characteristics of the power supply available, in different localities. I have also discovered that it is undesirable to utilize a step up transformer mounted within the same cabinet which contains the radio receiving apparatus as it is 85

30 35 40 45 50 55 60 65 70 75 80 85 90 95 100 105

Still another object of my invention is to provide a circuit arrangement for a plurality of electron tubes by which all of the cathode and anode circuits may be supplied with a steady source of direct current derived from a house lighting circuit without interference arising from fluctuations in the power supply for the elimination of all trace of hum in the radio receiving circuits.

Still another object of my invention is to provide a circuit arrangement in a radio receiving apparatus in which a plurality of tubes have their anode and cathode circuits all supplied from the same series circuit across which is impressed direct current energy properly smoothed out to eliminate noises arising from fluctuations existing in the current supply.

Still another object of my invention is to provide a series of resistances disposed in various parts of an electron tube receiving circuit, the resistances being distributed with respect to the cathode and anode circuits of the several electron tubes and tapped in connection with the tube electrodes for deriving the desired operating potential from the sev-

90 95 100 105

Still another object of my invention is to provide a series of resistances disposed in various parts of an electron tube receiving circuit, the resistances being distributed with respect to the cathode and anode circuits of the several electron tubes and tapped in connection with the tube electrodes for deriving the desired operating potential from the sev-

num type of rectifier operates particularly well. This rectifier may be connected directly in the line without the necessity of a step up transformer where 110 volts is available. Although half-wave rectified current may be utilized for efficient operation of the radio receiving circuits, I prefer to employ the Gratz arrangement of rectifier cells which gives a full wave rectified current which may be smoothed out to a fine degree. I, therefore, employ four rectifying cells, each composed of one aluminum electrode and one of iron or lead, or platinum immersed in a convenient electrolyte, as for example, borax, sodium or ammonium phosphate. The cells are connected with reversed polarity, as will be more fully pointed out hereinafter, in such manner that the alternating current energy may be impressed across one part of the circuit and direct current delivered at another part of the circuit. By this arrangement, I am enabled to secure a direct current voltage of approximately 90-95 volts across one part of the rectifier circuit, depending largely upon the efficiency of the chemical rectifier when 110 volts is employed from the line system. By shunting a large capacity across the output circuit of the chemical rectifier, I am able to obtain a much larger voltage approximately 124-125 volts. At the same time the amount of alternating current which enters the rectifier is considerably increased. The reason for this boosting up of the voltage is this: The rectifier current is fluctuating and it has a high negative component, or to put it differently, it can be analyzed into two components: one of which is a direct, non-fluctuating current, and the other is an alternating current. This latter component finds an easy path through the large capacity condenser and returns to the mains leaving only the direct current component, which being free from negative fluctuations, almost a straight line, will register a higher voltage on the direct current instrument. This current has practically the same characteristic as a direct current as generally obtained from power houses, but for my purpose this current must still be smoothed out in order to perfectly eliminate all trace of hum in the sensitive electron tube circuits.

After the direct current energy has been boosted to a relatively high value, I impress this energy upon a filter circuit consisting of one or several coils having iron cores which are paths of high impedances for alternating current components, and condensers of relatively large capacity which permit the alternating current components to return in the circuit and prevent such components from passing to the receiving apparatus. The arrangement of the condensers and high impedances in the filter circuit permits the alternating current components of

the energy to be by-passed while the direct current components of the energy are passed forward through the choke coils, according to the ohmic resistance encountered, but by using the proper size wire it can be so arranged that at the end of this filter the current should have the proper voltage which is approximately 90 volts.

The direct current energy is applied to a series circuit in a radio receiving apparatus. The receiving apparatus comprises electron tubes having cathode and anode circuits and the tubes themselves serve as resistances at proper parts of the series circuit. The series circuit also contains resistances connected in parallel which are tapped at proper points in order to obtain the proper voltages necessary in the various parts of the electron tube circuits. The drop along the series of resistances is employed in securing the proper operating potential for the several tubes. The resistances in the series circuit serve not only to secure a sufficient drop in the direct current voltage for supplying each of the cathode and anode circuits of the receiving apparatus, but also to obtain the necessary bias potential for the grids of the various tubes. The arrangement of the resistances in the series circuit is such that an accurate selection of the anode voltage and the grid biasing potential may be obtained for each tube in the receiving circuit and the correct cathode heating energy may be impressed upon each of the tubes for operating the tube at precisely the proper point on the characteristic curves thereof. In this manner I am enabled to obtain high operating efficiency in the receiving system and at the same time secure a high degree of convenience in operation of the receiving apparatus.

Referring more particularly to the wiring diagram, the invention has been illustrated in connection with a three stage radio frequency amplifier consisting of electron tubes 1, 2, and 3, detector 4, and audio frequency amplifier tubes 5 and 6. The receiving apparatus is connected to an antenna ground system represented by reference characters 7 and 8, including in series therewith a primary coupling coil 10, to which is coupled the secondary winding 12. The input circuit is tuned by condenser 14 and connected across the input terminals of electron tube 1. The electron tubes in the system contain the usual electrodes as represented at tube 1 as including cathode element 1^a, the control electrode 1^b and anode 1^c. The output circuit of electron tube 1 includes a primary winding 15 of coupling transformer 16 which is inductively related to secondary winding 17 tuned by variably tuned condenser 18, the circuit operating to impress amplified radio frequency energy upon the second stage of radio frequency

amplification which includes electron tube 2. The output circuit of electron tube 2 contains primary winding 19 of coupling transformer 20 which delivers the amplified energy to secondary winding 21 which may or may not be selectively tuned. The amplified energy is impressed upon tube 3, constituting the third stage of radio frequency amplification from which energy is delivered to primary winding 22 of coupling transformer 23 to the secondary winding 24. The energy in secondary winding 24 is impressed upon the detector tube 4 which includes grid leak and grid condenser 25 in the input circuit thereof. Energy is delivered by the detector tube 4 to the primary winding 26 of the audio frequency transformer 27, the secondary winding 28 of which connects to the input circuit of the audio frequency amplifier constituted by tubes 5 and 6 and intermediate coupling transformer 29. A suitable responsive device 30 has been indicated in the output circuit of the radio receiving apparatus. The power for energizing the anode circuits, heating the cathodes and placing the proper biasing potential on the grid electrodes is supplied by a connection to the line wire power supply system through leads 31 which connect to the four rectifying cells 32, 33, 34 and 35 arranged in reverse relationship as illustrated in the diagram. Each rectifying cell may be composed of one aluminum electrode designated by reference character 34^a of cell 34 and one iron or lead electrode designated by reference character 34^b or platinum immersed in a convenient electrolyte, as for example, borax, sodium or ammonium phosphate, as hereinbefore referred to. Direct current is delivered at terminal 36 which is positive and terminal 37 which is negative. A condenser 38 of relatively large capacity is shunted across the terminals 36 and 37 increasing the voltage delivered to the radio receiving apparatus as heretofore described. The filter system includes the iron core coils 39 and 40 and condensers 41 and 42 of relatively large capacity which by-pass alternating current components and prevent the delivery of these undesired components to the circuits associated with the radio receiving apparatus. The series circuit by which power is supplied to the electron tubes in the radio receiving circuit constitutes a resistance path 43 which is tapped at various points 44, 45 and 46 for the supply of a proper voltage to the anode circuits of the several tubes. The series circuit includes the cathodes of one or more of the tubes 1, 2, 3, 4, 5, or 6, with a return connection through the control rheostat 47 to the negative terminal 48 of the filter system. There is a drop in voltage from the positive terminal 49 of the filter circuit to point 50 in the series circuit due to the resistance 43 which is variable according to the current consumption in the number of cathodes of the tubes included in the series circuit. The arrangement of the taps 44, 45 and 46 is such that the anode potential may be selected for the several tubes to a fine degree and an accurate voltage value impressed upon the anodes of these tubes, that is a relatively high voltage for the audio frequency amplification tubes 5 and 6, a lower voltage for the radio frequency amplification tubes 1, 2 and 3, and a still lower voltage for the detector tube 4. The cathodes of the several tubes, being connected in series, provide a progressive drop in voltage along the series, such that points 51, 52, 53, 54, 55 and 56 may be tapped along the series circuit for the obtaining of a proper grid bias for the various tubes. Additional series resistances may be shunted across some or all of the cathode resistances of the several tubes and taps taken from such resistances to secure an accurate value of grid biasing potential. I have represented these resistances by reference characters 61, 62, 63, 64, 65, and 66 as connected in series and shunted across the cathodes of tubes 1, 2, 3, 4, 5 and 6 respectively. These resistances serve a double purpose, one function being to secure a proper grid bias for the various tubes of the system and the other purpose is to by-pass the current so as to protect the cathodes from excessive current. It will be seen that the anode current of every tube is added to the cathode current of each succeeding tube and as the cathodes are relatively fragile and very susceptible to harm from excessive currents I provide proper resistances across the terminals of the cathodes, which resistances decrease from tube to tube in proportion as the amount of current which must be bypassed increases from tube to tube. In order to secure a high degree of negative potential for biasing the grid of the last tube 6 an additional resistance 67 is provided in the circuit as shown and a tap taken from the point 68 to the grid of the adjacent tube 5 immediately preceding the last tube of the system. This method of biasing is followed generally for the other tubes in the system. That is to say, a tap 69 is taken from resistance 62 for biasing the grid of tube 1 immediately preceding the tube 2 having its cathode shunted by resistance 62. This is followed by biasing the grid of tube 2 by deriving the negative potential from a tap 70 on resistance 63, in shunt with the cathode of tube 3. Similarly, the grid of tube 3 is biased by potential derived from a tap 71 on resistance 64 in shunt with the cathode of tube 4. The grid of the detector tube 4 is operated at a positive potential by a tap taken to the negative terminal 48 of the filter system in series with condenser 72. In other words, the negative biasing poten-

tial from each of the tubes in the series is secured by selecting the drop in potential across the cathode circuit of a succeeding tube in the series. It will therefore be seen
 5 that the biasing potential may be very accurately selected, the cathodes each operated at the proper working temperature and the anode potential for each of the tubes accurately fixed, all in accordance with the
 10 characteristics of the tubes for operating the amplification system at maximum efficiency.

Where the energy supply is direct current rather than alternating current, as is the case
 15 in many parts of the United States, the direct current may be introduced at terminals 73 and 74 in the rectifier circuit without change in the radio receiving system. It is necessary however to make sure that the positive and negative terminals are properly connected in
 20 order that the apparatus may function. In the event that electrolytic condensers are used in the filter system an error in properly connecting to the current mains would cause a short circuit and damage to the line. On
 25 account of this, I prefer to use the same arrangement of rectifying cells for the direct current supply and to use the same input terminals as the ones used in connection with alternating current. It can be seen that in
 30 this case it makes no difference how these terminals are connected. They can be reversed but the direction of the current which comes out through 36 and 37 is always the same; 36 being always negative and 37 always positive. It will, therefore, be seen
 35 that the arrangement of the electrolytic cells may remain the same for both direct current and alternating current supply for the purpose of securing proper direction of the
 40 current in the circuit.

I find that in many instances it is quite practical to leave out the first resistance 61 and even the second and the third resistances when the tubes used are of a low voltage
 45 characteristic such as possessed by the WD 11 or 199 tubes. When this is done the proper grid bias may be obtained as from point 68 for example. As illustrated in
 50 Figs. 2 and 3 the resistances 61, 62, 63, 64, 65 and 66 of the proper ohmage may be connected between the negative terminal of a tube and any point which is more negative in value. The cathodes 1^a, 2^a, 3^a, 4^a, 5^a, and 6^a are connected in series, while resistances
 55 61, 62, 63, 64, 65 and 66 in Fig. 2 are arranged in shunt and series relationship with respect thereto. In Fig. 3, I have shown a circuit connection wherein the resistances 61, 62, 63 and 64 may be arranged in shunt with
 60 one or more of the cathodes 2^a, 3^a, 4^a, 5^a and 6^a for obtaining the proper grid bias.

It will be observed that the radio receiving system which I have described does not require a step up transformer which ordinarily introduces a large degree of hum in

the sensitive amplification circuits, interfering with the reproduction of the incoming signaling currents. My apparatus has been found very successful, convenient and efficient in operation.

While I have shown the filament electrodes of each of the tubes connected successively in series in the order represented in the drawing, I desire it to be understood that the sequence of the filaments may be varied, as for example, the filaments of the audio frequency amplifier tubes may be connected before the filament of the detector tube whereby these filaments are operated at more positive potentials thus enabling me to secure more negative bias on the grids of the audio frequency amplifying tubes without the use of the resistance such as #67. In changing the order or sequence of connection of the filaments, the resistance #67 may be omitted. Any desired order or sequence of the filaments may be employed in order to obtain proper grid biases.

In the claims I have pointed out that the chemical means which serve to obtain uni-directional current for the circuits of the electron tubes operates independently of the character of the power supply. By the character of the supply I mean whether the supply is of a direct or alternating current nature, and if alternating current, the frequency thereof is referred to as one of the characteristics of the supply. The said radio receiving apparatus is universal and operates on either alternating current or direct current without modification. That is to say the receiving apparatus operates on a supply system which may be direct as well as alternating.

While I have described my invention in a certain particular embodiment, I desire that it be understood that modifications may be made and that I intend no limitations upon the invention other than those imposed by the scope of the appended claims.

What I claim and desire to secure by Letters Patent of the United States is as follows:—

1. Radio receiving apparatus comprising in combination an amplification system, and a detector, including a plurality of electron tubes each having a cathode, grid and an anode, power supply means for said electron tubes, a power distribution circuit connected across said power supply means, and chemical means operating independently of the character of said power supply means for obtaining uni-directional current and means for energizing all of said cathodes and anodes of said electron tubes from said power distribution circuit.

2. Radio receiving apparatus comprising in combination a plurality of electron tubes, one of said tubes being arranged to function as a detector and others of said tubes being

arranged to operate as amplifiers, cathodes, anodes and grid electrodes for said tubes, power supply means for said electron tubes, a power distribution circuit connected across 5 said power supply means, means for obtaining uni-directional current from said power supply means independently of the character of said power supply means and connections between said cathodes and anodes with 10 points in said power distribution circuit for deriving operating potential for said electron tubes.

3. Radio receiving apparatus comprising in combination a plurality of electron tubes 15 each having a cathode, an anode and a grid, circuits interlinking said electrodes, a common source of power for said electron electrolytic tubes, means for obtaining uni-directional current from said source, a power 20 distribution circuit connected to said common source of power, said power distribution circuit including a series connection of said cathodes, and connections from said anodes to points along said power distribution 25 circuit for deriving a proper operating potential for said anodes from said common source of power, said circuits operating from direct as well as an alternating current source.

30 4. Radio receiving apparatus comprising in combination a plurality of electron tubes each having a cathode, an anode, and a grid, an input circuit for each of said tubes including the cathode and grid of each tube, 35 an output circuit for each tube including the anode and cathode thereof, with the output circuit of one of said tubes interlinked with the input circuit of a succeeding tube, a power supply system for said electron tubes, 40 means for obtaining uni-directional current from said power supply system, connections with said means including a power distribution circuit constituted in part by said cathodes, and connections from points in said 45 power distribution circuit to each of said anodes and grids for operating said tubes at a proper working potential, said circuits operating from direct as well as an alternating current source.

50 5. Radio receiving apparatus comprising in combination a plurality of electron tubes each having a cathode, an anode and a grid, an input circuit for each tube including the cathode and grid thereof, an output circuit 55 for each tube including the anode and cathode thereof, means interlinking the output circuit of one tube with the input circuit of a succeeding tube, a power supply system, an electrolytic rectifier connected 60 with said system for energizing said electron tubes said system including a power distribution circuit constituted in part by said cathodes, and connections along said power distribution circuit for usefully employing 65 the drop along said circuit for deriving a

proper working potential for each of said anodes and grids, said power supply being direct as well as alternating current.

6. In a radio receiving apparatus for universal operation from direct as well as alternating current power supply systems the combination of a plurality of electron tubes each having cathode, anode and grid electrodes, input and output circuits interconnecting said electrodes, with the output circuit of one of said tubes coupled with the input circuit of a succeeding tube, a source of current, a chemical rectifier connected with said source, and connections between said chemical rectifier and the circuits of 80 said electron tubes for supplying uni-directional current to said electron tubes independently of the character of said source.

7. A radio receiving apparatus for universal operation from direct as well as an 85 alternating current power supply comprising in combination a plurality of electron tubes each having grid, filament and plate electrodes, input and output circuits interconnecting said electrodes, with the output 90 circuit of one of said tubes coupled with the input circuit of a succeeding electron tube, a source of current, electrolytic means for obtaining uni-directional current from said source, and connections between said chemical means and the circuits of said electron tubes for supplying said uni-directional current to said electron tubes independently of the character of said source.

8. In a radio receiving apparatus the combination of a plurality of electron tubes each having a cathode, an anode, and a grid, resistance elements shunting said cathodes, a series circuit including said cathodes and a resistance, a source of current which may be 100 direct as well as alternating, means for obtaining uni-directional current, means for smoothing out the uni-directional current and applying said current to said series circuit, connections from said anodes to points 105 along said resistance and separate connections between said grids and variable points along said resistance elements, whereby uni-directional current may be applied to said cathodes, anodes and grids for operating 110 said tubes at the proper points on the characteristic curves thereof.

9. In a radio receiving apparatus for universal operation on direct as well as an alternating current power supply the combination 115 of a plurality of electron tubes each having a cathode, an anode, and a grid, a series circuit including said cathodes and a resistance, a source of alternating current, a chemical rectifier for deriving uni-directional current from said source, means for increasing the effective voltage of the rectified energy when alternating current is applied, additional means for smoothing out the rectified 120 energy and impressing said energy upon said 125

130

series circuit, and connections between points along said resistance and said anodes whereby the proper potential may be applied to said anodes for operating said electron tubes 5 at the proper points on their characteristic curves.

10. In a radio receiving apparatus for operation from direct as well as alternating current power supply the combination of a plurality of electron tubes each having a cathode, an anode, and a grid, a series circuit including said cathodes and a resistance, a source of current, means for deriving a uni-directional current from said source, means 15 for increasing the effective voltage of the energy thus developed when alternating current is supplied, means for smoothing out the rectified energy and applying said energy across said series circuit and adjustable connections along said resistance for said anodes whereby the proper potential may be applied to each of said electron tubes for operating 20 said tubes at the proper points on the characteristic curves thereof independently of the 25 character of said source.

11. In a radio receiving apparatus for universal operation on direct as well as alternating current power supply the combination of a plurality of electron tubes each having a 30 cathode, an anode, and a grid, of a series circuit including said cathodes and a resistance, a power supply circuit adapted to be connected to a source of alternating as well as direct current for supplying uni-directional 35 current to said series circuit, means interposed between said power supply circuit and said series circuit for smoothing out the uni-directional current delivered to said series circuit, and means connected to various 40 points along said resistance for deriving direct current potential for each of said anodes and grids, whereby said electron tubes may be operated at a proper point on the characteristic curves thereof independently of 45 the character of said power supply.

12. In a radio receiving apparatus for universal operation from direct as well as alternating current, the combination of a plurality of electron tubes each having a 50 cathode, an anode, and a grid, a series circuit including said cathodes and a resistance, a plurality of independent resistances connected in shunt with one or more of said cathodes, means for deriving negative bias 55 from said resistances for the grid of a preceding one of said electron tubes in the series, a power supply system connected to said series circuit, and connections from said anodes to points along said first mentioned resistance 60 whereby the proper operating potential may be impressed upon each of said electron tubes independently of the character of said power supply system.

13. A radio receiving apparatus for universal operation on direct as well as alter-

nating current power supply comprising in combination a plurality of electron tubes each having grid, filament and plate electrodes, input and output circuits interconnecting said electrodes, with the output circuit of one of said tubes coupled with the input circuit of a succeeding electron tube, a source of current, chemical means for obtaining uni-directional current from said source, means connected in shunt with said chemical means for boosting the voltage of the direct current component of the output of said chemical means when an alternating current source is connected therewith, and connections between said separate means and the circuits of said electron tubes for supplying uni-directional current to said said electron tubes independently of the character of said source.

14. In a radio receiving apparatus for universal operation from direct as well as alternating current power supply the combination of a plurality of electron tubes each having a cathode, an anode and a grid, a series circuit including said cathodes and a 90 resistance, connections from said resistance to said anodes, a uni-directional current supply system connected across said series circuit, chemical means for delivering uni-directional current to said series circuit independently of the character of said power supply, independent resistances connected in shunt with one or more of said cathodes, said resistances decreasing in value from tube to tube in proportion as the amount of current which must be by-passed increases from tube to tube, and means for deriving a negative biasing potential for the grid of a preceding one of said tubes either from the resistance shunting the cathode of the next succeeding tube in the series, or directly from the connection between the cathodes of two adjacent tubes whereby said electron tubes may be operated at a proper point on the characteristic curves thereof.

15. In a radio receiving apparatus, the combination of a plurality of electron tubes each having a cathode, anode and grid, a series circuit including said cathodes, and a resistance, a source of alternating as well as direct current, means for obtaining smooth uni-directional current and applying that current across said series circuit, and connections from said anodes to points along said resistance and connections from grid returns to points along the series of cathodes, whereby different potentials can be applied to said anodes and grids for operating said tubes at the proper points on the characteristic curves thereof independently of the character of said source.

16. A radio receiving apparatus for universal operation on direct as well as alternating current comprising in combination a

- plurality of electron tubes each having grid, filament and plate electrodes, input and output circuits interconnecting said electrodes, with the output circuit of one of said tubes 5 coupled with the input circuit of a succeeding electron tube, a source of current, chemical means for obtaining uni-directional current from said source, a circuit connected with said chemical means for smoothing out 10 the uni-directional current obtained from said source, and connections from said circuit to circuits of said electron tubes for supplying uni-directional current thereto free of fluctuations independently of the 15 character of said source.
17. A radio receiving apparatus arranged to operate universally from a direct as well as an alternating current power supply comprising a plurality of electron tubes each 20 having cathode and anode circuits, a power supply system and a chemical rectifier interposed between said circuits and said power supply system for supplying current to said circuits independently of the character of 25 said power supply system.
18. A radio receiving apparatus arranged to operate universally from a direct as well as an alternating current power supply comprising an electron tube amplification system, anode and cathode circuits for said electron tube amplification system, and a power supply system having input and output circuits with the output circuit thereof connected with said anode and cathode circuits 30 and the input circuit thereof connected to said power supply for supplying uni-directional current to said anode and cathode circuits.
19. A radio receiving apparatus arranged to operate universally from a direct as well as an alternating current power supply comprising an electron tube amplification system, anode and cathode circuits for said electron tube amplification system, and a power 35 supply system comprising a plurality of sets of electrolytic cells with connections between said sets to an output circuit and connections to said sets from an input circuit, said output circuit being connected to said anode and cathode circuits and said input circuit being connected to said power supply.
20. A radio receiving apparatus arranged to operate universally from a direct as well as an alternating current power supply comprising an electron tube amplification system, anode and cathode circuits for said elec- 40 tron tube amplification system, and a power supply system comprising separate pairs of chemical cell devices connected in series with the pairs thereof parallel connected to an input circuit with connections between said pairs to an output circuit, said output circuit being connected to said cathode and anode circuits and said input circuit being connected to said power supply. 45
21. A radio receiving apparatus arranged to operate universally from a direct as well as an alternating current power supply comprising an electron tube amplification system, anode and cathode circuits for said electron tube amplification system, and a power supply system, comprising separate branch circuits each including a pair of electrolytic devices connected in series with each branch circuit disposed in parallel and connected to said power supply and connections between individual electrolytic devices with said anode and cathode circuits for supplying uni-directional current thereto. 50
22. A radio receiving apparatus arranged to operate universally from a direct as well as an alternating current power supply comprising an electron tube amplification system, anode and cathode circuits for said electron tube amplification system and a power supply system, comprising a pair of branch circuits each including two electrolytic cells in series, with the branch circuits arranged in parallel, and connected with said power supply, a condenser shunted between individual electrolytic cells in each branch circuit and connections across said condenser for supplying uni-directional current to said anode and cathode circuits. 55
23. A radio receiving apparatus arranged to operate universally from a direct as well as an alternating current power supply comprising an electron tube amplification system, anode and cathode circuits for said electron tube amplification system and a power supply system comprising a pair of series and parallel paths interposed between said power supply and said anode and cathode circuits, whereby uni-directional currents are supplied to said circuits through one of said series paths when a direct current is supplied at said source and through two of said series paths when an alternating current is supplied at said source. 60

In testimony whereof I affix my signature.

MARCEL WALLACE.

DISCLAIMER

1,627,758. *Marcel Wallace*, New York, N. Y. RADIO RECEIVING APPARATUS.
Patent dated May 10, 1927. Disclaimer filed May 27, 1933, by the patentee.

Therefore, enters this disclaimer to claims 2, 4, 11, 15, and 18 in said specification which are in the following words:

"2. Radio receiving apparatus comprising in combination a plurality of electron tubes, one of said tubes being arranged to operate as amplifiers, cathodes, anodes and grid electrodes for said tubes, power supply means for said electron tubes, a power distribution circuit connected across said power supply means, means for obtaining uni-directional current from said power supply means independently of the character of said power supply means and connections between said cathodes and anodes with points in said power distribution circuit for deriving operating potential for said electron tubes."

"4. Radio receiving apparatus comprising in combination, a plurality of electron tubes each having a cathode, an anode and a grid, an input circuit for each of said tubes including the cathode and grid of each tube, an output circuit for each tube including the anode and cathode thereof, with the output circuit of one of said tubes interlinked, with the input circuit of a succeeding tube, a power supply system for said electron tubes, means for obtaining uni-directional current from said power supply system, connections with said means including a power distribution circuit constituted in part by said cathodes, and connections from points in said power distribution circuit to each of said anodes and grids for operating said tubes at a proper working potential, said circuits operating from direct as well as an alternating current source."

"11. In a radio receiving apparatus for universal operation on direct as well as alternating current power supply the combination of a plurality of electron tubes each having a cathode, an anode, and a grid, of a series circuit including said cathodes and a resistance, a power supply circuit adapted to be connected to a source of alternating as well as direct current for supplying uni-directional current to said series circuit, means interposed between said power supply circuit and said series circuit for smoothing out the uni-directional current delivered to said series circuit, and means connected to various points along said resistance for deriving direct current potential for each of said anodes and grids, whereby said electron tubes may be operated at a proper point on the characteristic curves thereof independently of the character of said power supply."

"15. In a radio receiving apparatus, the combination of a plurality of electron tubes each having a cathode, anode and grid, a series circuit including said cathodes, and a resistance, a source of alternating as well as direct current, means for obtaining smooth uni-directional current and applying that current across said series circuit, and connections from said anodes to points along said resistance and connections from grid returns to points along the series of cathodes, whereby different potentials can be applied to said anodes and grids for operating said tubes at the proper points on the characteristic curves thereof independently of the character of said source."

"18. A radio receiving apparatus arranged to operate universally from a direct as well as an alternating current power supply comprising an electron tube amplification system, anode and cathode circuits for said electron tube amplification system, and a power supply system having input and output circuits with the output circuit thereof connected with said anode and cathode circuits and the input circuit thereof connected to said power supply for supplying uni-directional current to said anode and cathode circuits."
